UNITED STATES PATENT OFFICE.

ARTHUR A. BACKHAUS, OF BALTIMORE, AND FRED B. ARENTZ, OF CURTIS BAY,
MARYLAND, ASSIGNORS TO U. S. INDUSTRIAL ALCOHOL CO., A CORPORATION
OF WEST VIRGINIA.

PROCESS OF MAKING ALDEHYDES.

1,388,841.

Specification of Letters Patent. Patented Aug. 30, 1921.

Application filed June 24, 1918. Serial No. 241,649.

To all whom it may concern:

Be it known that we, ARTHUR A. BACKHAUS, of Baltimore, in the State of Maryland, and FRED B. ARENTZ, of Curtis Bay, 5 in the county of Anne Arundel, and in the State of Maryland, have invented a certain new and useful Improvement in Processes of Making Aldehydes, and do hereby declare that the following is a full, clear, and 10 exact description thereof.

Our invention relates particularly to a process of producing aldehydes, but it has reference particularly to the production of acetaldehyde.

15 The object of our invention is to provide a process by means of which aldehydes, and particularly acetaldehyde, may be readily formed from the corresponding alcohol.

20 A further object is to carry out said process by means of a catalyst.

Further objects of our invention will appear from the detailed description thereof contained hereinafter.

25 While our invention is capable of embodiment in many different forms, for the purpose of illustration we shall describe only one form of our process hereinafter, and while said process is capable of being carried out with many different types of apparatus, for the purpose of illustration we have shown only one type of apparatus for use in connection therewith in the accompanying drawing, in which—

30 The figure is a diagrammatic representation, partly in section, of an apparatus which may be used in carrying out our invention.

35 In the drawing, we have shown an alcohol still 1, adapted to be heated by means of a steam jacket 2, having a vapor outlet pipe 3, which passes through a preheater 4, adapted to be heated in any suitable way, as for example by an oil jacket 4^a, having inlet and outlet pipes 4^b and 4^c. The tube 3 40 is connected to a catalyzer 5, which is comprised of a tube 6, carrying a quantity of granular porous material 6^a, such for example as pumice stone, unglazed porcelain, charcoal or terra cotta, carrying throughout 45 the same particles of a finely divided catalyzer metal, such for example as copper, nickel, chromium, or iron, which may be deposited therein by any suitable means, but preferably in such a manner as to involve 50 the reduction of an oxid of the metal by a

current of hydrogen, as for example by impregnating the carrier with a nitrate of the metal, precipitating with ammonia, drying, igniting and reducing with hydrogen.

Said catalyzer 5 is provided with any 60 suitable heating means, but may, for example, be provided for this purpose with a heating jacket 7, having inlet and outlet pipes 8 and 9, respectively, for supplying a current of highly heated oil thereto. A 65 tube 10 leads from the upper portion of the catalyzer 5 to a condenser 11, which is provided with the usual inlet and outlet pipes for cooling water 12 and 13, and which is adapted to condense the alcohol from the 70 vapors which pass out of the catalyzer 5. The condensed alcohol is caught in a cylindrical receiver 14 and may be drawn off by valved pipe 15, while the uncondensed 75 gases, comprising acetaldehyde and hydrogen, pass out by a pipe 16, which may contain a compressor 16^a, and thence to a condenser 17, adapted to be supplied with cooling water by inlet and outlet pipes 18 and 19. The compressor 16^a may be omitted if 80 desired, but, if omitted, the condenser 17 would be supplied with brine. The condenser 17 condenses the acetaldehyde, which is collected in a cylindrical receiver 20, having a valved draw-off pipe 20^a, while the 85 uncondensed gases, comprising the hydrogen formed in the process, are conveyed off by pipe 21, and may be discharged therefrom through a pressure relief valve 22.

In carrying out our process, a quantity 90 of an alcohol, such for example as ethyl alcohol, is introduced into the still 1, and is distilled therein by means of the heat applied by the steam jacket 2. The alcohol vapors are conveyed away by the pipe 3 to 95 the preheater 4, where the vapors are heated to a temperature of between 250° and 350° C., but preferably to approximately 300° C., before they enter the catalyzer 5, the temperature at which it is desired to act 100 upon the alcohol vapors in the catalyzer. The alcohol vapors, therefore, enter the catalyzer 5 at the required temperature, so that the formation of acetaldehyde immediately begins as soon as the vapors reach 105 the finely divided copper carried upon the granular particles within the catalyzer tube 6. The oil jacket 7 maintains the vapors in the tube at from 250° to 350° C., but preferably about 300° C., throughout the entire 110

length of said tube, and a large percentage of the alcohol vapors in thus decomposed to form acetaldehyde and hydrogen.

The vapors passing out of the catalyzer 5 by means of the tube 10 are conducted through the condenser 11, maintained at a temperature of 20—30° C., where any alcohol vapors present are condensed and are collected in the receiver 14, from which the 10 alcohol may be drawn off by means of the pipe 15. The acetaldehyde and the hydrogen pass out of the receiver 14 and are conducted to the compressor 16^a, where the gases are compressed to approximately 60 15 pounds per square inch. The compressed gases then pass through the condenser 17, maintained at a temperature of 10—20° C., where the acetaldehyde is condensed and collected in the receiver 20. In case the 20 compressor 16^a is not used, the temperature in the condenser 17 should be about 0° C. The hydrogen is conveyed away from the receiver 20 by the pipe 21, through the relief valve 22. The hydrogen may be collected in any suitable manner. In this way 25 the acetaldehyde is readily and continuously formed from the alcohol vapors formed in the still 1.

While we have described our invention 30 above in detail, we wish it to be understood that many changes may be made therein without departing from the spirit of our invention.

We claim:

35 1. The process which comprises preheating an alcohol vapor to a temperature lying between 250 and 350 degrees C., and passing

it through a catalytic agent comprising finely divided metallic particles maintained at about the above temperature, and separating out the aldehyde formed. 40

2. The process which comprises preheating an alcohol vapor to a temperature lying between 250 and 350 degrees C., passing the 45 vapors through a catalytic agent comprising finely divided metallic particles maintained at about the above temperature, and separating the aldehyde formed from the alcohol vapors by fractional condensation.

3. The process which comprises preheating 50 alcohol vapors to a temperature lying between 250 and 350 degrees C., passing them through a porous catalytic agent containing finely divided metallic particles maintained at a temperature substantially 55 as the above temperature and contained in a non-porous container, and separating the aldehyde formed from the alcohol and hydrogen.

4. The process which comprises preheating 60 ethyl alcohol vapor to a temperature lying between 250 and 350 degrees C., and passing the vapor through a catalytic agent comprising finely divided metallic particles maintained at about the above temperature, 65 and separating out the aldehyde formed.

In testimony that we claim the foregoing we have hereunto set our hands.

ARTHUR A. BACKHAUS.
FRED B. ARENTZ.
